UNITED STATES PATENT OFFICE.

ROBERT N. VAN BUSKIRK, OF DETROIT, MICHIGAN.

DRAFTSMAN'S PROTRACTOR.

1,157,825.

Specification of Letters Patent. Patented Oct. 26, 1915.

Application filed November 25, 1912. Serial No. 733,250.

To all whom it may concern:

Be it known that I, ROBERT N. VAN BUSKIRK, a citizen of the United States, residing at Detroit, county of Wayne, State of Michigan, have invented a certain new and useful Improvement in Draftsmen's Protractors, and declare the following to be a full, clear, and exact description of the same, such as will enable others skilled in the art to which it pertains to make and use the same, reference being had to the accompanying drawings, which form a part of this specification.

My invention relates to the construction of draftsmen's protractors, and my main object is to produce a high grade instrument that can be marketed at a low price. I attain this object in the device illustrated in the accompanying drawings in which:—

Figure 1, is a perspective view of a protractor embodying my invention. Fig. 2, is a perspective view of a portion of the base showing in detail the hole and recess or notch for the clamping screw and clamp heel respectively. Fig. 3, is a detail perspective 25 view of the clamp and screw. Fig. 4, is an underside view of the assembled protractor. Fig. 5, is a cross section taken on the line 1—1 of Figs. 1 and 4. Fig. 6, is a cross section taken on the line 2—2 of Figs. 1 and 30 4. Fig. 7, is a cross section taken on the line 3—3 of Figs. 1 and 4. Figs. 8 and 9 show an optional construction of the instrument as a whole with reversed relative positions of the base and sector.

A is a sheet metal die blanked and pressed base having two depressed straight edges α , and α' , at right angles to each other, the bisected angle of which passes through the point P, at which the base A, is pivoted to the sector B, the depressed portions α , and α' , rest upon the paper partly supporting the protractor; the object of the metal being bent down as shown in Figs. 5, and 6, to stiffen the base A, allowing the use of very thin metal which aids in making a light instrument.

c , and c' , are lips, which are formed on the base A, and lie in the same plane with the straight-edges α , and α' , and extend 50 underneath the sector B, to hold the circular

edge of the sector up in the proper plane, especially when the clamping nut E, is loosened for the purpose of changing angles; these lips also add rigidity to the assembled instrument, even when the base A, and sector 55 B, are securely clamped together, inasmuch as both the base and sector are held in the proper plane in relation to each other at the three points P, c , and c' , which are triangularly located. See Fig. 4. 60

d , is a segmental portion of the base A, depressed from said base to the same plane with, and abutting the sector B, upon which is stamped two sets of Vernier graduations reading to five minutes each in opposite directions from the bisected angle of the edges α , and α' , said graduations are numbered for each fifteen minutes from said bisected angle.

e , is an aperture in the base A, through 70 which the clamping screw D, extends vertically.

f , is a notch in the base A, in which the clamp heel i , is seated and held from turning in a horizontal plane.

g , g' , are openings in the base A, for the purpose of reducing weight.

B, is a sheet metal die blanked and pressed sector of an approximately semi-circular form, upon which are stamped graduations 80 in degrees to the extent of 110 degrees, which graduations are located along the periphery of the upper side and substantially in the middle of the sector arc, and are numbered for each 10 degrees from 0 to 90 degrees in 85 both directions beginning at the tenth graduation from either end; the extra unnumbered ten graduations at each end are necessary for the Vernier readings between 80 and 90 degrees; the sector B, being pivoted 90 to the base A, at the point P, the center of the outer circular edge of the sector.

b , is a depressed portion of the sector B, which forms a straight-edge, the length of which is approximately equal to the diameter of the circle of which the sector is a part, and rests upon the paper partly supporting the protractor; the fact of the metal being bent down as shown in Figs. 5 and 7, insures extra stiffness to the sector B, allow- 100

ing the use of very thin metal which aids in making a light instrument.

C, is a sheet metal die blanked and pressed clamp which lies substantially underneath the sector B, and into which the clamping screw D, is permanently fixed. The clamp C is drawn up against the sector B, which is held securely in place against the base A, by the thumb nut E, operating upon the 10 threads of the clamping screw D.

i, is the heel of the clamp C, which is turned upright and fits snugly into the notch f, of the base A.

j j, are shoulders on the heel i, of the 15 clamp C, which bear up against the sides of the notch f, of the base A, when the clamp is drawn tightly against the sector B.

k k, are shoulders on the heel i, of the 20 clamp C, which fit snugly against the edges of the notch f, of the base A, preventing the clamp C, from turning when adjusting the thumb nut E.

l, is the end of the clamp C, which bears up against the inner circular edge m, of the 25 sector B, holding the sector tightly against the base A.

n n, are openings in the sector B, for the purpose of reducing weight.

F, is a pivot bearing having an enlarged 30 end forming a shoulder which bears up against the underside of the sector B, said end having a flat side which lies parallel with, and abutting the shoulder h, of the sector B, preventing the pivot bearing F, 35 from turning except in the base A; the shank of the pivot bearing is a trifle longer than the combined thickness of the base and the sector, therefore when the screw G, is screwed tightly into F, the base and sector 40 will be held in place between the underside of the head of the screw G, and the shoulder on the pivot bearing F.

H, is a washer interposed between the 45 thumb nut E, and the base A, and fitting loosely over the clamping screw D; this washer may be of spring steel and the two halves bent at a slight angle with each other when free, for the purpose of holding the clamp C, up in place when the thumb nut 50 E, is loosened.

J, is an indicator stamped upon the base A, to indicate the angle between the straight-edges a and b.

K, is an indicator stamped upon the base 55 A, to indicate the angle between the straight-edges a' and b'.

While I have described the sector as placed under the base as shown, it is obvious that the relative positions of the base and sector may be reversed in this respect.

With the above construction a lighter instrument can be made because of the minimum number of parts as well as the very thin stock which can be used owing to the

acquired stiffness by bending. And because 65 of said reduction of parts, and of the die stamped graduations, and the other de- scribed simplifications, the cost to manu- facture will be unusually low for so high a grade an instrument. 70

What I claim is,—

1. In a protractor, the combination of a base, a sector lying under the base, said base having clips c c' bent downwardly and under said sector, said base having a portion bent downwardly so that its edge shall abut against the curved edge of said sector, said abutting edges being provided with co- 75 operating scales.

2. In a protractor, the combination of a 80 base having straight edges a a' bent downwardly, a sector lying below said base and being provided with lips c c' extending under said sector, and having their lower surfaces in the plane of the supporting por- 85 tion of said base.

3. In a protractor, the combination of a base, a sector lying under said base, said base being provided with a notch f, a clamp upon said base adapted to engage under said 90 sector and provided with a heel i, adapted to engage in said notch.

4. In a protractor, the combination of a base and a sector, a pivot bearing having a flattened edge portion joining said base and 95 sector, said sector being provided with a shoulder h, against which said flat portion bears.

5. In a protractor, the combination of a base and a sector arranged under said base 100 of a clamp having an upwardly extending heel with shoulders adjacent to the lower end thereof, said base being provided with an aperture f, said heel being adapted to engage in said aperture and said shoulder 105 against the surface of said base.

6. In a protractor, the combination of a base, a sector pivoted to the base and having one face near its circumferential edge slid- 110 ingly engaging one face of the base and members attached to the base at widely spaced points thereon for engaging the other face of the sector adjacent its circum- ferential edge to guide the said sector in its rotative movement with respect to the base. 115

7. In a protractor, the combination of a base having two intersecting straight edges that can rest on the surface where the pro- 120 tractor is used, a sector pivoted to the base, the main portion of the base being raised above the surface to provide a span greater than the thickness of the sector, the said sector provided with a straight edge capable of resting upon the said surface when used, the main part of the sector being raised 125 above the said surface but somewhat less than the spacing of the main part of the base, the said sector being thereby adapted

to swing in under the base but spaced from the underlying surface, means for pivoting the sector to the base, and means for holding the circumferential edge of the sector against the under side of the base and securing the same in various angular relations with respect to the base.

In testimony whereof, I sign this specification in the presence of two witnesses.

ROBERT N. VAN BUSKIRK.
